UNITED STATES PATENT OFFICE

172,002

TOY FLYING SAUCER

Donald C. Browne, Vancouver, British Columbia,
Canada

Application June 16, 1953, Serial No. 25,513

Term of patent 7 years

(Cl. D34—15)

To all whom it may concern:

Be it known that I, Donald C. Browne, a citizen of Canada and a resident of the city of Vancouver, in the Province of British Columbia, Canada, have invented a new, original, and ornamental Design for a Toy Flying Saucer, of which the following is a specification, reference being had to the accompanying drawings, forming a part thereof.

Figure 1 is a side elevational view of a toy flying saucer, showing my new design;

Figure 2 is a front elevational view thereof; and

Figure 3 is a top perspective view thereof.

I claim:

The ornamental design for a toy flying saucer, as shown.
